DESIGN FOR A KNOB FOR RADIODIALS

Application filed February 24, 1928. Serial No. 25,566. Term of patent 3½ years.

To all whom it may concern:

Be it known that I, JOHN GELOSO, a citizen of the Kingdom of Italy, residing in the borough of Manhattan, in the city, county, and State of New York, have invented a new, original, and ornamental Design for a Knob for Radio Dials, of which the following is a specification, reference being had to the ac-

companying drawing, forming part thereof.

Fig. 1 is a plan view of the device.

Fig. 2 is a side elevation in section through line 2—2 of Fig. 1.

I claim:

The ornamental design for a knob for radio dials, as shown.

JOHN GELOSO.
